UNITED STATES PATENT OFFICE

BENJAMIN SMITH, OF CHELSEA, MASSACHUSETTS

DESIGN FOR AN EDIBLE CONTAINER FOR ICE CREAM

Application filed October 30, 1929. Serial No. 33,221. Term of patent 7 years.

To all whom it may concern:

Be it known that I, BENJAMIN SMITH, a citizen of the United States, residing at Chelsea, in the county of Suffolk and State of Massachusetts, have invented a new, original, and ornamental Design for Edible Containers for Ice Cream, of which the following is a specification, reference being had to the accompanying drawing, forming a part hereof.

Fig. 1 is a top plan view of an edible container for ice cream, showing my new design; Fig. 2 is a side elevational view; and Fig. 3 is an edge elevational view of the same.

I claim:

The ornamental design for an edible container for ice cream, as shown.

BENJAMIN SMITH.
